(57) **CLAIM**

The ornamental design for an easel holder, as shown and described.

DESCRIPTION

FIG. 1 is a front, left, top perspective view of an easel holder, showing my new design;

FIG. 2 is a rear, right, bottom perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of detail 9 in FIG. 1;

FIG. 10 is an enlarged view of detail 10 in FIG. 2;

FIG. 11 is an enlarged view of detail 11 in FIG. 3;

FIG. 12 is an enlarged view of detail 12 in FIG. 4;

FIG. 13 is a sectional view of the enlarged scale of 13-13 along the line in FIG. 7;

FIG. 14 is a front, left, top perspective view of the easel holder, indicating the usage environment; and,

FIG. 15 is an enlarged view of detail 15 in FIG. 14.

The broken lines in the figures are for the purposes of illustrating portions of the easel holder and form no part of the claimed design. The dash-dot-dash broken lines are for notating enlarged views and form no part of the claimed design. The broken lines depicting an easel are included for environmental purposes only and form no part of the claimed design.
